UNITED STATES PATENT OFFICE.

WILLIAM FULLER HOSFORD, OF OAK PARK, ILLINOIS, ASSIGNOR TO WESTERN ELECTRIC COMPANY, INCORPORATED, OF NEW YORK, N. Y., A CORPORATION OF NEW YORK.

TAPE OR RIBBON WORKING MACHINE.

Application filed December 21, 1923. Serial No. 682,126.

This invention relates to tape or ribbon working machines, and more particularly to a machine adapted to be used for the inspection of metal tapes.

5 An object of this invention is to provide a machine capable of subjecting simultaneously both sides of a tape to the scrutiny of an operator.

Another object of this invention is to provide 10 a machine whereby both sides of a metal tape or the like are slowly conveyed before an operator, enabling said operator to brush, scrape, or otherwise remove any defects from both sides of the tape before the 15 said tape is taken up on a take-up spool.

In accordance with the general features 20 of the invention there is provided a material supply source, an examining table, over which the material passes twice, exposing one side the first time and the opposite side the second time, and a power driven take-up mechanism which draws the material from the supply source over the examining table onto the take-up reel.

25 Another feature of this invention is the provision of means for the reversing of a tape ribbon, web, or the like, between a supply and a take-up spool.

Still another feature of the invention is 30 the provision of means for maintaining a constant tension on a metal tape traveling between a supply and a take-up spool.

Other objects and advantages of the invention will more fully appear from the 35 following detailed description taken in connection with the accompanying drawings which illustrate one embodiment thereof.

In the drawings,

40 Fig. 1 is a front view of a machine embodying the features of this invention;

Figs. 2 and 3 are reduced fragmentary plan and side views respectively of the mechanism shown in Fig. 1, and

45 Fig. 4 is an enlarged detail horizontal sectional view of the tensioning mechanism of the machine.

Referring now to the drawings in detail in which like reference numerals designate similar parts throughout the several views, 50 10 indicates a bench (Fig. 3) to which is secured a supply reel holder 11, in which a supply reel 12 is rotatably mounted on a stud 13, which passes through the center of the supply reel and is suitably secured 55 at its ends in the holder 11.

Secured to the bench 10 in front of the holder 11 is a wooden block 14 (Fig. 3) which is slightly rounded as indicated at 15, to provide a smooth guiding surface for the tape 16 which is to be inspected. A 60 tensioning device, indicated at 17, is mounted on the aforesaid wooden block 14 and comprises essentially a clamping plate 18, at the ends of which are secured two blocks 19 and 20 which may be made of rubber 65 (Fig. 4). These rubber blocks 19 and 20 are held in place by two bolts and nuts 21 and 22. The aforementioned clamping plate 18 is in turn held in the forepart of the wooden block 14 by two bolts 23 and 24 70 which project respectively through two countersunk bores 25 and 26 in the wooden block 14. Surrounding the two bolts 23 and 24 respectively are two compression springs 27 and 28 whose ends rest against the shoulder of countersunk bores 25 and 26 and washers 29 and 30, which are held in place by wing nuts 31 and 32.

Located on top of the bench 10 and immediately over the tensioning device 17 are 80 two grooved pulleys 35 and 36 (Fig. 1), which are rotatably mounted in a bracket 38 formed on the end of an examining table 39. Pivotedly secured in a bracket 40, which is located under the supply reel holder 11, 85 is an idle pulley 41. Suitably located at the rear of the examining table 39 is a take-up reel 42 which is rotatably mounted on a shaft 49, which is driven by a constantly rotating pulley 44 connected by a belt 46 with a pulley 45 secured to a shaft 47 which is actuated by any suitable source of power (not shown).

A friction clutch 48 of usual and well known type serves to connect and disconnect the shaft 49 to and from the pulley 44, the clutch being operated through a leverage mechanism comprising a foot lever 50, a link 51, lever 52, lever shaft 53, and a lever 54, said last-mentioned lever having a yoke 100 member 55 which straddles a clutch operating member 56.

The operation of this mechanism is as follows:

The supply reel 12 is placed in the holder 11 and the tape 16 which is to be inspected is drawn from the underside of the said reel 12 up to the guiding surface 15 of the wooden block 14 (Fig. 3). The tape 16 is then passed between the wooden block 14 and the 110

rubber block 19 of the tensioning device 17. The operator now draws the tape 16 over the grooved pulley 35 onto one side of the examining table 39. From the table 39 the tape 16 is pulled down through an opening in the bench 10 (Fig. 3) and reversed as indicated at 60. The operator then threads the tape 16 under the idle pulley 41, the side of the tape 16 that has just been exposed on the table 39 being now made the inner side, and up to the wooden block 14. The tape 16 is then passed between the wooden block 14 and the rubber block 20 of the other side of the tensioning device 17 (Fig. 4).
15. By adjusting the wing nuts 31 and 32 (Fig. 4), the pressure of the rubber blocks 19 and 20 on the tape 16 may be varied, thus enabling the maintenance of a constant tension on the tape 16. The operator now draws 20 the tape 16 from the tensioning device 17 over another grooved pulley 36, which is adjacent to the grooved pulley 35, onto the opposite side of the examining table 39, exposing the unexamined side of the tape 16 25 and lastly onto the take-up reel 42. Both sides of the tape 16 are now exposed to the scrutiny of the operator. By depressing the foot lever 50 (Fig. 1) the operator causes an actuation of the clutch 48 to couple the 30 shaft 49 to the constantly rotating pulley 44 to cause the take-up reel 42 to rotate and

draw the tape from the supply reel through the machine in the manner already described.

What is claimed is:

- 35 1. In a machine for working ribbons, a supply source, a take-up device, a work table having a surface to contact with a ribbon, means for passing two strips of ribbon over the work table moving in the same direction and at the same speed, and means for delivering the ribbon to the table in such a manner that both sides thereof will be exposed.
- 40 2. In a machine for working metallic ribbons, a supply source, a take-up device, a work table having a surface to contact with a ribbon, said ribbon being reversed between the supply and take-up device, driving means for the take-up device whereby the 45 ribbon is withdrawn from the supply source and passes twice over the table each time moving in the same direction and at the same speed and in contact with the surface of the table, and brake devices engaging different 50 sections of the ribbon for applying tension thereto.
- 55 3. In witness whereof, I hereunto subscribe my name this 13th day of December A. D., 1923.

WILLIAM FULLER HOSFORD.
